UNITED STATES PATENT OFFICE.

MATTHEW HARRIS NICHOLSON, OF TYLER, TEXAS, ASSIGNOR TO
EUGENE ROSENBAUM, OF DALLAS, TEXAS.

CULTIVATOR.

No. 841,171.

Specification of Letters Patent.

Patented Jan. 15, 1907.

Application filed September 26, 1906. Serial No. 336,379.

To all whom it may concern:

Be it known that I, MATTHEW HARRIS NICHOLSON, a citizen of the United States, residing at Tyler, in the county of Smith and State of Texas, have invented a new and useful Cultivator, of which the following is a specification.

This invention relates to cultivators; and its object is to provide a device of this character having oppositely-disposed series of teeth, said series being independently adjustable in relation to the beam of the cultivator and having means whereby the adjustment can be quickly and easily effected.

A still further object is to provide simple means for locking the teeth in adjusted position.

With the above and other objects in view the invention consists of certain novel features of construction and combinations of parts, which will be hereinafter more fully described, and pointed out in the claims.

In the accompanying drawings is shown the preferred form of the invention.

In said drawings, Figure 1 is a plan view of the cultivator, showing in full lines one of the positions which may be assumed by the teeth and another position being shown by dotted lines; and Fig. 2 is a longitudinal section through the cultivator, parts thereof being broken away.

Referring to the figures by characters of reference, 1 is the beam of the cultivator, having handles 2 extending from the rear end thereof, while secured to the bottom of the beam is a guide-plate 3, having longitudinally-extending slots 4 therein, one slot being disposed at each side of the beam. A pivot-bolt 5 extends through the beam, and mounted thereon are the overlapping ends of front cross-strips 6 and 7, extending laterally in opposite directions from the beam. Each of these cross-strips has a brace 8 fastened to it, and the two braces overlap above the beam 1 and are pivotally mounted on the upper portion of the bolt 5. Another bolt 9 extends through the beam in rear of the bolt 5, and pivoted thereon are oppositely-extending cross-strips 10 and 11, the ends of which overlap. The cross-strips 6, 7, 10, and 11 are connected by parallel teeth 12, said teeth being pivoted to the cross-strips at their points of intersection therewith. Said cross-strips are maintained parallel at all

times by the teeth, and as the strips extending to the left of the beam are separate from the strips extending to the right thereof it is obvious that the teeth at the two sides of the beam can be independently adjusted. One of the teeth 13 is held in place solely by the bolts 5 and 9 and is disposed directly under the beam. This tooth is not, therefore, adjustable. A link 14 is pivoted to the strip 10 and another link 15 to the strip 11, and the inner ends of these links ride upon the plate 3 and have upturned ears 16, adapted to bear against opposite faces of the beam 1. Levers 17 and 18 are fulcrumed upon opposite sides of the beam 1, and a rod 19 connects the lever 18 with link 14, while another rod 20 connects lever 17 with link 15. The forward ends of these rods project downward through the slots 4 and have means thereon, such as cotter-keys 21, for preventing the rods from being withdrawn from the slots. Toothed segments 22 are mounted on the beams, one being provided for each lever 17 and 18, and a spring-pressed dog 23 is carried by each lever and adapted to engage a segment, so as to lock the lever in any position to which it may be adjusted.

It will be seen that by constructing a cultivator in the manner herein described either the right or the left series of teeth may be adjusted forward or backward simply by manipulating the proper lever. The two series of teeth may be arranged as shown in full and dotted lines in Fig. 1, or said positions may be reversed. The adjustment is quickly effected by means of the levers, and when the parts have once been adjusted they are securely locked by means of the dogs and segments. Importance is attached to the fact that the rods 19 and 20 not only serve to transmit motion from the levers to the links, but also hold the links in position upon the plate 3 and prevent the parts from becoming displaced. By providing the upturned ears 16 the links are prevented from biting into the beam during the adjustment of the cultivator.

What is claimed is—

1. In a cultivator the combination with a beam; of a pair of cross-strips pivotally connected to the beam, a series of teeth pivoted to the cross-strips, a longitudinally-slotted guide-plate secured to the beam, a link pivoted to one of the cross-strips and slidably

mounted on the guide-plate, means for actuating the link, and means extending from the link and into the slotted plate for retaining the link upon the plate.

- 5 2. In a cultivator the combination with a beam; of oppositely-extending cross-strips pivotally connected thereto, a series of teeth pivoted to the cross-strips and maintained in fixed relation thereby, a guide carried by the beam, links slidably mounted upon the guide and pivoted to the cross-strips, independent means for sliding the links upon the guide, and retaining devices extending from the links and engaging the guide.
- 15 3. In a cultivator the combination with a beam; of oppositely - extending pairs of cross-strips pivotally connected to the beam, a series of teeth pivoted to each pair of cross-strips, a longitudinally - slotted guide secured to the beam, links pivoted to the pairs of cross-strips and slidably mounted on the guide, actuating-levers, and rods connecting
- 20

25 said levers and the links, said rods extending through the slots and constituting retaining means for the links.

4. In a cultivator the combination with a beam; of oppositely - extending pairs of cross-strips pivotally connected to the beam, a series of teeth pivoted to each pair of cross-strips, a longitudinally-slotted guide secured 30 to the beam, links pivoted to the pairs of cross-strips and slidably mounted on the guide, actuating-levers, rods connecting said levers and the links, said rods extending through the slots and constituting retaining 35 means for the links, and means for locking the levers in adjusted position.

In testimony that I claim the foregoing as my own I have hereto affixed my signature in the presence of two witnesses.

MATTHEW HARRIS NICHOLSON.
